UNITED STATES PATENT OFFICE

JESSE GUTMANN, OF BROOKLYN, NEW YORK, ASSIGNOR TO FERDINAND GUTMANN & CO.,
OF BROOKLYN, NEW YORK, A CORPORATION OF NEW YORK

POURING LIP FOR CONTAINERS AND METHOD OF APPLYING SAME

Application filed July 26, 1930. Serial No. 470,862.

My invention relates to pouring lips for containers and a method of applying same to containers and it is my object to provide bottles, jars, cans and the like with a pouring 5 lip which will control the flow and enable drops to be counted and which will prevent the contents running down the outside of the container after pouring so that the outside of the container will present a clean appearance and be sanitary. The invention is especially applicable to containers provided with screw caps as it keeps the threads clean and free from foreign matter so that the cap may be easily applied and removed. In 10 practicing my invention the pouring lip is assembled with the cap and affixed to the container at the same time the cap is applied and as the cost of the pouring lip is very 15 small the cost of packaging is not materially increased.

In the drawings Fig. 1 is a view of a container with my pouring lip, slightly exaggerated for clearness of illustration; Fig. 2 a plan view of a pouring lip; Fig. 3 a sectional view of a cap with a pouring lip therein ready to be placed on a container; and Fig. 4 a side view of a container, the top edge 25 partly broken away, ready to receive the pouring lip.

The invention comprises a thin washer 1, best shown in Fig. 2, which is adhered to the top surface of the container mouth 2. The washer is preferably made of a transparent material inert to the container contents and 30 its outside diameter is slightly larger than the outside diameter of the container mouth so that when pouring the contents will run over a thin, sharp edge and will not run down the outside of the container, the amount 35 of the extension of the pouring lip beyond the container mouth may be varied as occasion requires. The diameter of the central opening in the washer is preferably approximately the same as the inside diameter of the 40 container mouth.

In commercial practice the cap 3 has a gasket 4 inside to effect the seal and the washer 1 is placed inside the cap, over the gasket, but not necessarily adhering thereto as it may adhere slightly to prevent displacement 50 during handling in the capping machine. After the containers are filled they pass under a gumming machine which applies a layer of suitable adhesive, preferably one not affected by the container contents, to the 55 top surface of the container mouth. The adhesive coated containers then pass to the capping machine where the caps are driven home to seal the containers. The washer 1 will then adhere to or unite with the top surface of the container so that when the cap is removed the pouring lip will remain on the 60 container.

When the pouring lip is applied in this manner it is preferably composed of a 65 springy material which will snap back into a flat, or nearly flat, shape after the distortion incident to inserting it into and removing it from the cap.

Adhesion between the washer and the top 70 surface of the container mouth may also be effected by a suitable solvent instead of an adhesive, by coating the washer with an adhesive material and applying moisture, by the application of heat, or by other means. 75

Instead of a large central opening the washer may have a plurality of openings for use as a sprinkler top.

I claim:—

1. A pouring lip for containers comprising a thin washer with a central opening therein united to the top surface of a container mouth, with its outside edge projecting beyond the outside periphery of the 85 mouth.

2. A pouring lip for containers comprising a thin washer of transparent material, provided with a central opening therein, united to the top surface of a container 90

mouth with its outer edge projecting beyond the outside periphery of the mouth.

3. A pouring lip for containers comprising a thin washer provided with a central opening united to the top surface of a container mouth with its outside edge projecting beyond the periphery of the mouth but not interfering with the application of a cap to the container.

10 4. A pouring lip for containers comprising a thin washer provided with a central opening united by means of an adhesive to the top surface of a container mouth with its outside edge projecting beyond the periphery of the mouth.

In testimony whereof I have affixed my signature.

JESSE GUTMANN.
